No. 15.103.

June 24, 1884.

Woolen Knit Skirt

UNITED STATES PATENT OFFICE.

MARY TURNER, OF NEW YORK, N. Y., ASSIGNOR TO THE BUTTERICK PUBLISHING COMPANY, (LIMITED,) OF SAME PLACE.

DESIGN FOR A MISS'S WALKING-SKIRT.

SPECIFICATION forming part of Design No. 15,103, dated June 24, 1884.

Application filed May 12, 1884. Term of patent 3½ years.

To all whom it may concern:

Be it known that I, MARY TURNER, of the city, county, and State of New York, have invented and produced a new and original Design for a Pattern of a Miss's Walking-Skirt, (numbered 9,213;) and I do hereby declare that the engraved prints accompanying this specification convey to any one accustomed to using paper patterns a clear understanding of how a garment made up by the pattern will appear.

The design shows a round walking-skirt that displays a lower front drapery extending nearly to the foot of the skirt, and exhibiting a

plaited fan at the center and three plain panels 15 at each side, a short tablier-drapery displaying gatherings at its back edges, and a deep full back drapery exhibiting draping plaits in its front edges and loopings at the center.

What I claim as my invention, and desire to 20 secure by Letters Patent, is—

The design for a miss's walking-skirt, as shown in the engraved prints accompanying this specification.

MARY TURNER.
